UNITED STATES PATENT OFFICE.

ALBERT C. FISCHER, OF KANSAS CITY, MISSOURI.

REVOLUBLE ENGINE.

1,301,547.

Specification of Letters Patent. Patented Apr. 22, 1919.

Application filed February 15, 1917. Serial No. 148,879.

To all whom it may concern:

Be it known that I, ALBERT C. FISCHER, a citizen of the United States, residing at Kansas City, in the county of Jackson and State 5 of Missouri, have invented certain new and useful Improvements in Revoluble Engines, of which the following is a specification.

This invention relates to a revoluble wheel tire and has reference to a wheel or engine 10 having a non-revoluble, central annular frame to provide bearings for a revoluble tire, useful as a band-wheel or for traction or other purposes, one of its objects being to apply a driving power at or near the periphery of the tire.

The invention consists of the novel construction, combination and arrangement of parts as described herein and claimed, and as illustrated in the accompanying drawing, 20 wherein,—

Figure 1 is a view of the device in side elevation, parts being broken away and in section. Fig. 2 is a sectional view of the same longitudinally of the tire. Fig. 3 is a 25 sectional view through the wheel on line 3—3 of Fig. 2. Fig. 4 is a transverse section on line 4—4 of Fig. 2. Fig. 5 is a transverse section on line 5—5 of Fig. 2. Figs. 6 and 7 are enlarged, detail views showing 30 a clutch. Fig. 8 is a sectional view on line 8—8 of Fig. 2. Fig. 9 is a sectional view on line 9—9 of Fig. 2. Fig. 10 is a broken away view of the engine or wheel in side elevation to illustrate means for readjusting the pistons and for expelling exhaust gases.

While the invention is illustrated and described in connection with the expansive force of ignited gas as a source of power, I do not wish to be understood as limiting 40 myself in this respect, nor to size, form, proportion or minor details of construction further than determined by the scope of the appended claims.

In the drawing, which illustrates one embodiment of the invention, I have shown a 45 non-rotatable support consisting, in part, of a central bracket 1 provided with a spindle 2 upon which, by means of keys 3, is secured a hub 4 having radially disposed spokes ar- 50 ranged in pairs, as the pairs 5, 5', and 6, 6' and the pair 7, 7', the outer ends of the spokes being provided with a rim or annular tire-support 8; the hub, spokes and rim thereby providing a non-revoluble wheel- 55 member or support. Numerals 9 indicate a

pair of bearing-blocks which are stationary with respect to the rim and which project outwardly of the ends of the spokes 7 and 7'.

At 10 is indicated an annular casing or 60 tire, substantially of U-shape in cross-section, its end walls or sides being adapted to engage numerous balls or rollers 11 which are disposed in suitable grooves formed in the opposed annular recesses 12 of the rim 65 8, and means are provided to cause a revoluble movement of the tire on said bearings, consisting in part, of the pair of segmental cylinders 13 and 14, these being secured within and at diametrically opposed parts 70 of the casing, each being provided with a central, longitudinally curved tube 15.

A two-faced ring gear 16 is provided and is disposed substantially at the middle of the tire, within and movable through the tubes 75 15. It is adapted to have bearings upon balls or rollers 17 which are interposed between the inner part of the ring gear and the bearing-blocks 9. As best shown in Fig. 3, idler gears are employed in pairs 80 and arranged in the tire, as the pairs 18 and 19, the gears for each pair being disposed upon opposed sides and engaging the ring gear, and mounted in the blocks 9 for rotation, said gears also engaging the opposed 85 annular racks 20 of the tire.

Numerals 21 and 22 respectively indicate curved pistons and curved piston rods for the cylinders. Each piston rod is of tubular form and circumscribes and is adapted to 90 have slidable movements on a tube 15. Also each piston rod is provided at its outer end with a clutch, best shown in Figs. 6 and 7, each clutch consisting, in part, of a housing 23 secured to a piston rod by a keeper 24 95 disposed in a slot 25 formed in the housing. Numeral 26 indicates a pawl for each clutch, said pawl being provided with a tail-piece having an inclined face or contacting-part *a*, and it will be understood that when a piston 100 is actuated for moving a piston rod outwardly of a cylinder, the piston rod may have a limited movement within the housing 23 for engaging the inclined part *a* of the pawl to thereby move the tooth of the 105 pawl into engagement with the ring gear, the outward movements, in alternation, of the piston rods and the pawls, operating to move the ring gear. When a piston begins its movement inwardly of a cylinder 110

the pawl will be released from the ring gear on account of the form or inclination of its inner wall *b*, said wall being disposed at an obtuse angle to the longitudinal axis of the 5 tooth.

Hydrocarbon is conducted to each cylinder in alternation by actuation of the pistons. At 27 (Fig. 9) is indicated a passageway formed in the bracket 1 in communication with any suitable source of gas fuel supply and in communication with the passageway 28 formed in the spindle 2, the latter passageway also being in constant communication with passageways 29 and 29' 10 of the respective spokes 5 and 5'. When the piston of the cylinder 13 moves toward the front end of said cylinder, the gas will enter the rear end thereof, by suction from passageway 29 by passing the tube 30 and check 15 valve 31 (Figs. 1, 2). At 32 is indicated a conduit communicating with the rear end of cylinder 13 and with the front end of the cylinder 14, and it is obvious that a rearward movement of the piston of the cylinder 18 will cause the gas to enter the cylinder 14, said gas not being permitted to return, 20 since such return will be prevented by reason of a check valve 33.

Hydrocarbon is conducted to the front 30 end of the cylinder 13 in a manner similar to that just described. When the piston of cylinder 14 moves toward the front end thereof, a charge of gas, by operation of suction, will enter the rear end of said cylinder from passageway 29' by passing a tube 34 and check valve 35. A conduit 36 communicates with the rear end of the cylinder 14 and with the front end of the cylinder 13, and a rearward movement of the piston of cylinder 14 will cause the gas to enter the cylinder 13, and by means of a check valve 37, the gas will be prevented from returning.

Numerals 28' indicate spark plugs provided for the cylinders, and any suitable arrangement may be made for sparking, so that the charges of gas in the cylinders will be ignited in alternation and at the time the gas is compressed therein, at each complete 45 rotation of the tire. Means are shown and will be described for causing ignition of gas in the cylinder 13, this being considered sufficient since the construction and arrangement of parts for this purpose is the same 50 for both cylinders. At 38 (Fig. 1) is indicated a conductor electrically energized by any suitable means, and adapted to electrically energize a horizontally projecting brush 39 which is suitably insulated and 55 mounted on a yoke 40 carried by a block 9. Numeral 41 indicates a second brush which is also insulated and mounted on said yoke, this last named brush being in communication with an adjacent spark plug by means 60 of an electrical conductor *c* as plainly shown

in Fig. 1. By this construction the electrical circuit is incomplete between the brushes 39 and 41. By referring to Fig. 3. It will be seen that the inner side of the tire is provided with a pair of insulated contact-blocks 70 42 electrically in communication by means of a conductor 43, and it will be understood that, during a complete rotation of the tire, the blocks 42 carried thereby will make contact with the brushes 39 and 41, this contact 75 completing the electrical circuit to cause a sparking for igniting the gas within the cylinder 13.

By the construction as described the tire is provided with a single pair of contact-blocks, and during a complete rotation of the tire said pair of blocks are engaged by the brushes disposed near and at the front of both of the cylinders, whereby sparking for the cylinders is accomplished, the piston rods moving outwardly of the cylinders in alternation, the clutches gripping and moving the ring gear, the movement of said ring gear in one direction causing the tire to rotate in an opposite direction on account 80 of the pairs of beveled gears 18 and 19, the momentum of the tire being depended upon for causing a part of its rotatable movement while not engaged by a clutch, if only two cylinders are employed, as shown. 95

In order that the pistons may be completely reciprocated to expel exhaust gases and for compressing the charges of gas, devices are provided consisting, in part, of a pair of pinions 44 best shown in Fig. 4, 100 having rotatable bearings in the rim 8. Numeral 45 indicates an actuating arm or curved rack-bar disposed between and engaged by the pinions 44, said arm being mounted upon the piston rod of the cylinder 13. 105

Numerals 46 indicate a pair of actuating arms or curved rack-bars (Fig. 4) each being engaged by a pinion 44, said arms 46 being connected with a yoke *d* which is 110 mounted on the piston rod of the cylinder 14, and by this construction it will be understood that when the piston rod of cylinder 13 moves outwardly, the arm 45 will move in the same direction, and it will cause the pair of actuating arms 46 to move, simultaneously therewith, in a reverse direction to the movement of said arm 45, to thereby move the piston of cylinder 14 inwardly, this inward movement causing the new 115 charge of hydrocarbon which has entered said cylinder 14, to be compressed, the spent gases having been previously expelled by the entrance of said new charge as is usual with two-cycle engines. 120

As thus described it will be understood that when the piston rod of the cylinder 14 moves outwardly, the pair of arms 46 will move in the same direction, and will cause the arm 45 to move in a reverse direction 130

to the movement of said arms 46 for moving the piston of the cylinder 13 inwardly, said inward movement causing the exhaust gases to be expelled from the cylinder 13, and 5 causing the fuel gas which enters therein to be compressed.

By referring to Figs. 2, 8 and 9, it will be seen that the exhaust gases may move outwardly from the cylinder 13 by entering the narrow pockets *e* formed in the bottom of said cylinder, and from thence moving through the passageway 47 of the spoke 6, and after entering the passageway 48 of the spindle, may move out of the passageway 49 of the bracket-support 1, the exhaust gases from the cylinder 14 moving outwardly by passing similar passageways *e*, 47, 48 and 49.

Having fully described the several parts 20 and their uses, a further explanation relating to operation is not necessary.

What I claim and desire to secure by Letters Patent is,—

1. In a revoluble engine, a support, an annular casing having bearings on the support and provided with an annular rack, a ring gear in the casing, toothed gears engaging the ring gear and annular rack, a cylinder within the casing provided with a 25 tube circumscribing the ring gear, a piston arranged for longitudinal reciprocation within the cylinder with bearings on said tube and provided with a tubular extension circumscribing said ring gear, and a coupling device carried by the tubular extension of the piston for engaging said ring gear during one of the movements of said piston.

2. In a revoluble engine, a support including an annular rim provided outwardly 40 thereof with bearing-blocks, roller-members on the bearing-blocks, an annular casing mounted on the roller-members and provided with annular racks, a ring gear in the casing, toothed gears engaging the ring gear and annular racks, a pair of cylinders within the casing each being provided with a tube circumscribing the ring gear, pistons arranged for longitudinal reciprocation within the cylinders each bearing on a tube 45 of a cylinder and provided with an extension circumscribing said ring gear, and a pair of clamping members, each being mounted slidably on the tubular extension of a piston for causing a movement of the ring gear during one of the movements of a piston.

3. In a revoluble engine, a support, a circular casing circumscribing the support, a ring gear within the casing, a cylinder within 55 the casing, a piston arranged for longitudinal reciprocation within the cylinder and having a tubular extension circumscribing the ring gear and projecting outwardly of the cylinder, a clutch on the tubular extension of the piston for moving the ring

gear during one of the movements of said piston, and means for communicating the movements of the ring gear to the casing.

4. In a revoluble engine, a support provided with bearing-blocks having grooves 70 formed therein, roller-members in the grooves of the bearing-blocks, a circular casing circumscribing the support, a ring gear within the casing on said roller-members, a curved cylinder within the casing having a 75 tubular part encircling the ring gear, a piston bearing upon the tubular part of the cylinder and arranged for longitudinal reciprocation, said piston having a tubular extension bearing on the tubular part and projecting outwardly of the cylinder, a clutch slidably mounted on the tubular extension of the piston for moving the ring gear during one of the movements of the piston, and means for communicating the movements of 80 the ring gear to the casing.

5. In a revoluble engine, a support provided with a rim having annular grooves for containing roller-members and being further provided with bearing-blocks having 90 grooves for containing roller-members, a casing circumscribing the support and bearing upon the roller-members of said rim, a ring gear within the casing bearing upon the roller-members of the bearing-blocks, a 95 cylinder in the casing, a piston arranged for longitudinal reciprocation within the cylinder, for moving the ring gear in one direction, and coöperating devices within the casing for communicating the movement of the 100 ring gear to said casing.

6. In a revoluble engine, a support provided with an endless rim having a pair of endless grooves for containing roller-members, said support being further provided with a plurality of bearing-blocks each having a groove for containing roller-members, a circular casing bearing upon the roller-members of said rim and provided with an annular rack, a ring gear bearing upon the roller-members of said bearing-blocks, a cylinder in the casing having a tubular part circumscribing the ring gear, a piston bearing upon the tubular part of the cylinder and adapted to be reciprocated longitudinally for rotating the ring gear, and toothed gears on the bearing-blocks for communicating the rotatable movement of the ring gear to the casing.

7. In a revoluble engine, a support including a pair of bearing-blocks and a circular rim, a circular casing having an annular rack and mounted on said rim, a ring gear within the casing on said bearing-blocks, toothed gears engaging the rack of the casing, said gears being in engagement with and revoluble by the ring gear for rotating the casing, and means for rotating the ring gear including a cylinder of segmental 125 form circumscribing said ring gear and a 130

piston adapted to be reciprocated longitudinally within the cylinder, said piston having a tubular extension arranged to engage the ring gear during one of its longitudinal movements.

8. In a revoluble engine, a support, an annular casing having bearings on the support and provided with annular racks, a pair of pinions axially mounted in the casing, a ring gear in the casing, toothed gears engaging the ring gear and annular racks, a pair of cylinders within the casing each being provided with a tube circumscribing the ring gear, conduits disposed between the adjacent ends and in communication with the cylinders, pistons bearing on the tubes of the cylinders and adapted to be moved in one direction for rotating the ring gear to communicate a rotatable movement to the casing, and a plurality of rack-bars engaging the axially mounted pinions of the casing and movable by said pistons.

9. In a revoluble engine, a support, a circular casing circumscribing the support, a ring gear within the casing, gear wheels engaging the ring gear and said casing, cylinders of segmental form within the casing, pistons within the cylinders circumscribing the ring gear, each piston being provided with a clamping member, means for moving the pistons outwardly of the cylinders in alternation to cause actuation of the clamping members for communicating a rotatable movement to the ring gear, and means for moving the pistons inwardly of the cylinders in alternation.

10. In a revoluble engine, a support provided with toothed gears arranged in pairs, a ring gear having bearings on the support and engaging the toothed gears, a circular casing circumscribing the ring gear and provided with annular racks engaging the toothed gears, a pair of cylinders of segmental form disposed in the casing, a pair of conduits each being disposed intermediate the adjacent ends and in communication

with said pair of cylinders, a pair of pistons circumscribing the ring gear each being disposed within a cylinder and having an outwardly projecting tubular part provided with a clamping device, means for moving the pistons in alternation outwardly of the cylinders for causing engagement of the clamping members with the ring gear, and means for moving the pistons, in alternation, inwardly of the cylinders.

11. In combination, a non-revoluble support having a circular rim provided with endless grooves for containing roller-members, a circular casing circumscribing said rim to bear upon the roller-members and provided with an annular rack, a ring gear in the casing on the support, a plurality of tubular members circumscribing the ring gear and provided with clutch-members, said tubular members being movable in one direction, in alternation, for moving the ring gear, and a plurality of toothed gears in the casing for communicating the movement of the ring gear to said casing.

12. In a revoluble engine, a support including an annular rim provided outwardly thereof with bearing-blocks, roller-members on the bearing-blocks, an annular casing mounted on the roller-members and provided with annular racks, a ring gear in the casing, toothed gears engaging the ring gear and annular racks, said toothed gears being revoluble by actuation of the ring gear for rotating the casing, a plurality of tubular members circumscribing the ring gear and provided with clutch-members, said tubular members being movable in one direction, in alternation, for actuating the ring gear.

In testimony whereof, I have affixed my signature in presence of two witnesses.

ALBERT C. FISCHER.
